United States Patent Office

Des. 189,211
Patented Nov. 8, 1960

189,211

TRANSIT LEVEL

Elwin W. Davis, La Vale, Md., assignor to C. L. Berger & Sons, Inc., Boston, Mass., a corporation of Massachusetts

Filed Apr. 30, 1959, Ser. No. 55,706

Term of patent 14 years

(Cl. D52—1)

Fig. 1

Fig. 2

Fig. 4

Fig. 5

Fig. 1 is a side perspective view of a transit level, showing my new design.

Figure 2 is a top plan view.

Fig. 3 is a perspective view of the side opposite to that shown in Fig. 1, with the telescope partially elevated.

Fig. 4 is a front elevational view.

Fig. 5 is a rear elevational view.

I claim:

The ornamental design for a transit level, substantially as shown.
